Patented Apr. 8, 1919.

UNITED STATES PATENT OFFICE.

CHAUNCEY B. FORWARD, OF URBANA, OHIO.

METHOD FOR REFINING OIL.

1,299,449.

Specification of Letters Patent. Patented Apr. 8, 1919.

Application filed December 6, 1917. Serial No. 205,815.

To all whom it may concern:

Be it known that I, CHAUNCEY B. FORWARD, a citizen of the United States, residing at Urbana, in the county of Champaign 5 and State of Ohio, have invented certain new and useful Improvements in Methods for Refining Oil, of which the following is a specification.

This invention relates to a method for refining oil, and is an improvement on the method for treating petroleum shown and described in my application for Letters Patent of the United States, Serial Number 155,695, filed March 19, 1917. The object of 10 the present invention is to heat the oil gradually to a higher temperature than I find possible under my former practice, and in so doing separate a larger percentage of the volatile substances from the product being 15 treated and reducing such volatile substances to a finer gaseous state permitting fractional separations therefrom.

In the accompanying drawing, I show a diagrammatic view of an apparatus for 20 practising the invention, comprising a steam superheating boiler 2, three separate oil heaters 3, 4 and 5, respectively, an oil pump 6 to force feed the oil in a continuous stream under a high pressure through said oil heaters, a primary separator 7 into which the 25 heated oil is discharged and from which the volatile and gaseous substances are fed, a series of clarifying condensers 8 connected in tandem for clearing and separating the less volatile substances having a lower 30 Baumé gravity test than the gasolene or motor fuel oil desired, and a worm condenser 9 and liquid separator 10 for the gasolene or motor fuel oil.

40 In practising the method, the crude oil or other product to be treated, is forced from its supply tank 11 by pump 6 in a continuous stream into and through a long coil of relatively small pipe 12 confined within 45 the cylindrical heater 3 which is heated to a high temperature by superheated steam. To be more specific, the steam temperature maintained constantly in heater 3 is about 450° F. Thence, the oil flows at a temperature 50 of about 420° F. to a second long coil of relatively small pipe 13 confined within the second cylindrical heater 4 which is heated by superheated steam obtained directly from the steam superheating boiler 2 55 by way of a valved pipe 14. A practical

working steam temperature at the point where the steam leaves the boiler is about 850° to 950° F. and where this superheat temperature is maintained a temperature of approximately 600° F. is maintained in oil 60 heater 4, and the steam from cylinder 4 may be delivered through a pipe 15 to heater 3 and utilized therein to pre-heat the oil to about 420° F. as stated. These temperatures are more or less dependent on the speed with 65 which the oil is pumped through the coils. The temperature being reduced with increased speed of oil. Under these conditions a constantly flowing body of oil may be heated and discharged into a separator in a 70 highly-volatile condition, but I have discovered that a higher efficiency in result may be obtained by subjecting the twice heated oil to further heating, and that a higher steam temperature can be maintained 75 constantly within a third cylindrical heater 5, providing that the heated oil issuing from the coil of pipe 13 is carried through a third coil 16 contained within a cylindrical heater 5 receiving a supply of live superheated 80 steam direct from the boiler at about the same temperature as delivered to heater 3 where superheated steam is delivered at about 850° F. to 950° F. to pipe 14 and the supply pipe 17 for heater 5 which connects with 85 pipe 15. The steam temperature maintained within the third heater 5 is approximately 700° to 750° Fahrenheit, while the oil passing to coil 16 is about 550° to 600° Fahrenheit and is caused to issue from the coil at 90 about 650° to 750° Fahrenheit.

The problem is to secure a high degree of temperature on the oil before being atomized by the superheated steam, into the separator while the oil is passing through 95 the heated coil at a rate rapidly enough to make it commercially economical and practical. Thus in practising the steps as described, the oil issues from the third coil at about a temperature of 650 to 750° 100 Fahrenheit and is commingled with superheated steam of higher temperature obtained directly from the superheater through pipe 18 which connects with the discharge pipe 19 before entering the upper 105 end of the separator or still 7. Consequently, the oil and steam ejected into the separator are in a highly-volatilized state and under an extremely high temperature 110 and also pressure, the pressure in the sep-

arator being maintained in operations by a suitable pressure regulating valve 20 in the vapor or gas discharge pipe 21 leading from the top of the separator to the bottom of the 5 first clarifier or condenser 8 of the series of three connected in tandem as shown in the drawing. The residuum collecting in separator 7 is drawn off at its bottom through a valved drain pipe 22, while the separations 10 from each clarifying condenser 8 are drawn off through their respective gage columns 23 located at the bottom thereof. The pressure in the separator forces the residue through valve controlled pipe 22 to tanks 15 located any desired distance from apparatus as is likewise the case with the oils of heavier gravity than gasolene from clarifying condenser 8. These valves are opened just sufficient in each case to allow the products 20 to flow out as fast as they accumulate so that the operation is continuous. The gasolene or motor fuel is delivered in a water-white condition without acid alkali or filtration treatment into a suitable tank 25 24 subsequently to its passage through the worm condenser 9 and liquid separator 10 where the condensed steam is separated from the gasolene or motor fuel oil and the outflow of the refined product is uninterrupted 30 and continuous during pumping and heating operations as described. The same steps may proceed under lower temperatures than above stated or at higher temperatures where it is feasible to superheat and maintain the steam at higher temperatures and 35 pressure economically, but the present disclosure is predicated on operations proceeding with the use of a steam boiler and superheater yielding a constant supply of steam 40 at a temperature of 850 to 950° Fahrenheit and 200 to 300 pounds pressure, and with the connecting pipes, oil heaters and

separator adequately protected by suitable insulating material.

What I claim is:

1. A method of refining oil, consisting in subjecting a flowing body of oil to steam superheated to a temperature below 500° Fahrenheit; then subjecting the heated oil while still flowing to a higher temperature than as stated but not exceeding a temperature which would coke the oil or any part thereof; and finally reheating the product preliminary to discharging the oil in a volatilized state with steam into a still. 55

2. A method of refining oil, consisting in forcing a stream of oil continuously through plural sets of coils of pipe, heating one set of coils by superheated steam and utilizing the same steam at a lower temperature in 60 heating a second set of said coils, and heating another set of said coils by a new supply of superheated steam to further heat the oil before ejecting the same into a separator. 65

3. A method of refining oil, consisting in pumping a body of oil through separate sets of coils of pipe while subjecting each set to superheated steam maintained at a high temperature, then continuing the flow of oil 70 through further coils of pipe heated by superheated steam to a temperature higher than the maximum temperature of the steam in the first sets, then commingling superheated steam with the heated oil and 75 ejecting the mixture into a closed vessel under a sustained pressure, and finally delivering the separate products into different containers.

Signed at Cleveland, in the county of 80 Cuyahoga, and State of Ohio, this 17th day of November, 1917.

CHAUNCEY B. FORWARD.
